UNITED STATES PATENT OFFICE.

ARMAND A. TIBBITS, OF SOUTH OMAHA, NEBRASKA.

MUSIC-LEAF TURNER.

1,190,045.

Specification of Letters Patent.

Patented July 4, 1916.

Application filed March 27, 1915. Serial No. 17,447.

To all whom it may concern:

Be it known that I, ARMAND A. TIBBITS, a citizen of the United States, residing at South Omaha, in the county of Douglas and State of Nebraska, have invented certain new and useful Improvements in Music-Leaf Turners; and I do hereby declare the following to be a full, clear, and exact description of the invention, such as 10 will enable others skilled in the art to which it appertains to make and use the same.

This invention relates to music leaf turners and has for its principal object to provide a device which is adapted to be folded 15 and carried in the pocket of the user.

Another object of the invention is to provide a simple and efficient device which may be easily and quickly put into operation so that the pages of sheet music may be easily 20 and quickly turned without inconvenience to the operator.

A further object of the invention is to provide a novel means for controlling the turning of the sheets of music which is 25 carried within easy reach of the user so that little difficulty will be encountered in the operation of the device.

With these and other objects in view the invention consists in the novel combination 30 and arrangement of parts which will be fully set forth in the following specification and accompanying drawings, in which:

Figure 1 is a perspective view of the music leaf turner in its folded position. Fig. 35 2 is a longitudinal sectional view of the device in its open position. Fig. 3 is a top plan view of the device in its open position showing the cover removed. Fig. 4 is a transverse sectional view taken on the line 40 4-4 of Fig. 2. Fig. 5 is a detail view of the music support showing the same folded. Fig. 6 is a detail view of one of the clips 45 formed on the ends of the upright, illustrating the bifurcation to receive a sheet of leaf music, and Fig. 7 is a detail view of one of the clips on the end of the arms to receive a corner of a sheet of music.

Referring to the drawing, the numeral 1 designates as an entirety the main body of 50 the device which comprises the bottom 2 having secured thereto the side walls 3 and 4 and the end walls 5^a. The wall 3 forms the front wall of the device and is formed with suitable apertures 5 for the reception 55 of the operating shaft which will be more fully hereinafter described. Hinged to the end walls 5^a of the device as at 6 are the

covers designated generally by the numeral 7 each of which are substantially half of the length of the body 1 and comprises the 60 top 8 having the side walls 9 and the end walls 10. The cover may be secured to the base in a closed position by means of a hook 11 or other suitable fastening means as clearly shown in the drawing. 65

Secured within the body 1 near each end are the partition walls 12 which form a central chamber in which the operating mechanism is mounted. These partition walls are provided with openings 13 which 70 form guides for the sliding bars 14 which bars are formed with racks 15 on one side and the racks 16 on the under side. Extending through the apertures 5 in the front wall 3 and journaled in suitable bearings 75 carried by the rear wall are the horizontal shafts 17 which are provided at their outer ends with the thumb pieces 18 by which they are rotated. Suitable gears 19 are mounted on the shafts and are arranged to mesh 80 with the racks 16 as clearly shown in Fig. 2. While in the present invention there are shown three bars 14 it is to be understood that any number may be used without departing from the spirit and scope of the invention. Journaled in suitable bearings 85 carried by the bottom wall 2 of the body 1 are the vertically extending shafts 20 carrying the gears 21 which mesh with the racks 15. Formed on the gears but spaced 90 upwardly therefrom are suitable disks 22 which are provided with apertures 23 for the reception of the lug carried by the music support which will be more fully hereinafter described. The shafts 20 are 95 formed with axial bores which coöperate with the apertures 23 in supporting the music holders in proper place.

The music holders above referred to are designated generally by the numeral 24 and 100 each consists of the tubular standards 25, 25^a and 25^b, in which the uprights 26, 26^a and 26^b are slidable. The uprights are bifurcated at their upper ends and bent over as at 27 to form clips in which the edge of the 105 music to be supported is placed. The uprights 26 may be adjusted vertically to hold leaf music of different sizes and are held in their adjusted position within the standards 25 by the set screws 28. Pivoted as at 29 110 near the lower ends of each of the standards 25, 25^a and 25^b are arms 30, having formed at their free ends suitable clips 31 for the reception of the opposite corners of the music

leaves. A suitable arcuate guide 32 is carried by each of the standards 25, 25^a and 25^b and formed with a slot for the reception of a suitable guide pin extending through each 5 arm 30 as clearly shown in the drawings. Depending from the pivoted portion of the standards are suitable cylindrical extensions 33 which are arranged to extend into the axial recess in the ends of the shaft 20 in 10 which they are held. Lugs 34 are carried on the arms 30 and these lugs engage in the aperture 23 in the disks 22 heretofore described. It will thus be seen that the standards are supported in the shafts and are held against 15 relative rotation by means of the disks 22 and lugs 34 respectively, so that any music leaf placed on the supports will be turned upon movement of the respective rod 14.

In the explanation of the operation of the 20 device, the reference characters A, B and C will represent the thumb pieces by means of which the shafts A', B' and C' are controlled. These shafts carry their respective 25 gears A², B² and C² which mesh with their respective rack bars A³, B³ and C³. Meshing with the racks 15 of the respective rack bars are the gears a, b and c which are mounted on the shaft. It will thus be seen that when the thumb piece A is rotated the shaft A' 30 will also rotate thereby causing the gear A² to move the bar A³. This will cause the gear a to rotate and thereby turn the shaft d in its bearing and thus cause the sheet of music carried by the standard 25 mounted on said 35 shaft to be turned, so that the opposite side thereof will be exposed. When it is desired to turn the second sheet of music the thumb piece B is turned and this will cause the shaft B' to rotate thereby moving the 40 gear B² so that the rack bar B³ will slide through its bearings and cause the rack 15 to engage the gear b and turn the same, thus rotating the shaft e carrying the standard 25^a, whereby the second sheet of music is 45 turned. The same operation is gone through in turning the third sheet of music by the manipulation of the thumb piece C and it will thus be seen that a device is provided which will easily and quickly turn the pages 50 without inconveniencing the user.

While in the foregoing there has been shown and described the preferred embodiment of this invention it is to be understood that such changes may be made in the combination and arrangement of parts as will fall within the spirit and scope of the appended claims.

What is claimed is:

1. A device of the character described including a casing, bars slidably mounted in 60 said casing, racks formed on the sides and under faces of the bars, vertical shafts journaled within said casing, gears carried by

said vertical shafts and adapted to mesh with the racks upon the sides of said bars, 65 disks secured to the free ends of said vertical shafts and spaced from the gears, tubular standards mounted in the vertical shafts, music leaf holders secured to the ends of said tubular standards, horizontal shafts 70 journaled in said casing, gears mounted on said horizontal shafts and adapted to mesh with the racks upon the under faces of the bars, thumb pieces carried by the free ends of said horizontal shafts to rotate said horizontal shafts to move the bars laterally of the casing to rotate the music leaf holders about a vertical axis. 75

2. In a device of the character described including a casing, bars slidably mounted in 80 said casing, vertical shafts journaled in said casing, racks formed on said bars, gears carried by said vertical shafts to mesh with said racks, means to move the bars laterally of the casing to rotate said vertical shafts, 85 disks secured to the upper ends of said vertical shafts and provided with a side aperture therein, said vertical shafts provided with a recess in the ends thereof, tubular standards having extensions formed thereon 90 to be received within the recesses, arms pivoted to said tubular standards, lugs carried by said arms and engaging the apertures of the disks, and means carried by the ends of the arms and tubular standards to receive 95 the corners of leaf music.

3. In a device of the character described including a casing, bars slidable within said casing, racks formed on said bars, means for manually operating said bars to slide them 100 laterally of said casing, vertical shafts journaled in said casing, gears carried by said shafts and adapted to mesh with the racks of said bars, disks provided with side apertures carried by said vertical shafts, said 105 vertical shafts provided with recesses in the ends thereof, tubular standards having extensions formed on the lower ends to be received by said recesses, arms pivoted to said standards adjacent the lower ends of the 110 latter, pins carried by said arms and engaging the apertures of the disks, uprights adjustably secured to said tubular standards, said uprights provided with the ends curved and bifurcated to form clips, said arms provided with their free ends curved and slotted to form clips, said last mentioned clips adapted to receive one corner of leaf music and the first mentioned clips to receive the 115 opposite corner of the leaf music. 120

In testimony whereof I affix my signature in presence of two witnesses.

ARMAND A. TIBBITS.
